TIRE

Gilbert Joseph Hoke, Kenmore, N.Y., assignor to Dunlop
Tire and Rubber Corporation, Buffalo, N.Y.

Filed Jan. 30, 1970, Ser. No. 21,158

Term of patent 14 years

Int. Cl. D12—14

U.S. Cl. D90—20

FIG. 1

FIG. 2

FIG. 3

FIG. 4

FIG. 1 is a perspective view.

FIG. 2 is a side view of the outer side of the tire, it being understood that the shoulder design on the inner side of the tire is identical.

FIG. 3 is a fragmentary front view showing the tread and shoulders, it being understood that the tread and shoulder design continues uninterruptedly around the peripheral surface of the tire.

FIG. 4 is a cross-section taken on a radial plane as seen in FIG. 3.

The characteristic features of my invention reside in the design of the tread and shoulder.

I claim:

The ornamental design for a tire, as shown and described.
